LATCH

Robert L. Sayles, Meriden, Kans., assignor of one-half to Stewart K. Sayles, Meriden, Kans.

Application February 3, 1941, Serial No. 377,232

1 Claim. (Cl. 292—236)

My invention relates to latches and has as one of the principal objects thereof the provision of a latch organization which may be easily applied to doors, gates and the like and which may be conveniently operated from either side of the door without undue effort on the part of the operator.

An important object of my invention is to provide a device of the character described which is simple in construction, durable in use, efficient in operation and economical in manufacture.

Other objects and advantages will be apparent from the following description, appended claim and annexed drawings.

Referring to the drawings wherein like reference characters designate like parts throughout the several views:

Figure 1 is a side elevation of my invention in connected relation with a gate and gate post.

Figure 2 is a sectional view taken on the line 2—2 of Figure 1.

Figure 3 is a sectional view taken on the line 3—3 of Figure 1.

Figure 4 is a perspective view of the latch casing and latch bar and with the same illustrated in disassembled relation.

Figure 5 is a perspective view of one of the latch bar operators.

Figure 6 is a perspective view of the keeper.

Figure 7 is an end elevation of the latch and illustrating a modified arrangement of the latch bar operators.

In practising my invention, as illustrated in Figures 1 to 6 inclusive of the drawings, I provide a latch organization comprising a latch casing 5 secured to the front end of a gate 6 and a keeper 7 secured to a gate post 8, it being understood that the gate is adapted to pivot with respect to the post. The latch casing 5 is fashioned with detachable front and rear sections 9 and 10 respectively and with said sections secured together by means of nuts and bolts 11 or the like. The side walls 12 are cut and bent in a manner to form substantially anterolaterally disposed brackets 13 and with the latter defining the contours of registering openings 14 in the walls 12 as clearly illustrated in Figures 1 and 4 of the drawings.

The section 10 is formed with top, bottom, front end and rear end walls 15, 16, 17 and 18 respectively and with the front and rear end walls 17 and 18 fashioned with elongated slots 19 and 20 respectively. The slot 19 is disposed intermediate the top and bottom walls 15 and 16 while the slot 18 is disposed in close proximity to the 55

top wall 15 for a purpose hereinafter made apparent.

Postjacent the opening 14, the wall 12 of the section 10 has threaded therein one end of an inwardly disposed pivot or screw 21, the latter having pivotally mounted thereon a latch bar or element 22 provided with front and rear end portions 23 and 24 respectively. The inner ends of the portions 23 and 24 effect jointure with each other at the pivot 22 while their respective outer ends extend through the slots 19 and 20. The outer end of the rear portion 24 is provided with a weight 25 for urging the upper face of the front portion of the bar in engagement with the face defining the upper end of the slot 19.

Each of the brackets 13 is provided with an aperture 26 through which extends a bolt 27 pivotally and interjacently connected to a bell crank lever or latch bar operator 28. The lower end 29 of the lever 28 extends through the adjacent opening 14 of the side wall and overlies the upper face of the front portion of the bar 23 prejacent the pivot 21. The end 29 of each of the levers 28 extends in close proximity to horizontality while the other end 30 extends upwardly in close proximity to verticality as clearly illustrated in Figure 2. Both of the ends 29 of the levers 28 engage one of the upper faces defining one of the openings 14 whereby to maintain the ends 30 in raised position.

The keeper 7 comprises a plate 31 formed with a pair of elongated slots 32 through which extends screws 33 for securing the keeper to the gate post 8, the elongation of the slots permitting vertical adjustment of the keeper with respect to the post and the latch bar 22 as apparent from an inspection of Figure 3 of the drawings. The upper end of the plate is formed with a right angularly disposed section 34 extending towards the casing 5 and terminating in close spatiality therewith. The sides of the section 34 are fashioned with bearings 35 in which are rotatably mounted horizontal pintles 36, the latter being provided at one end with normally depending portions 37 and at their opposite ends with horizontally disposed portions 38 normally engaging the upper face of the section 34 and precluding outwardly swinging of the portions 37. The side walls 12, postjacent the brackets 13, are formed with registering openings 39 through which is inserted a pin 40 for overlying engagement with the bar 22 to preclude accidental operation of the bar to open position, as hereinafter set forth, by cattle or the like. The pin 40 is secured to one of the walls 12 by a chain 41 or the like.

In operation, the parts being in the positions illustrated in full lines in Figures 1 to 3 inclusive, pressure is exerted on the upper end 30 of one of the levers 28 to actuate the upper end in a direction towards the gate. When pressure is thus exerted on the lever the latter actuates the front portion of the bar downwardly and below the lower ends of the portions 37 of the pintles 36 and at the same time effect swinging of the gate to an open position beyond the post.

When the gate is operated from opened to closed position, it is swung toward the keeper, (the bar being disposed in horizontality by the weight 25 as hereinbefore described) whereupon the bar engages a depending portion 37 of the adjacent pintle and rotates said depending portion inwardly and upwardly to a point where it becomes released from the bar and gravitates to normal verticality thus positioning the bar between the portion 37 of both of said pintles. Due to the portions 38 of the pintles engaging the section 34, the depending portions 37 are precluded from outwardly and upwardly pivoting thereby maintaining the bar interposed between the portions 37 when said bar is in the aforementioned horizontal position. From the foregoing it will be apparent that the gate may be freely opened by merely exerting sufficient pressure upon the upper end of one of the levers 28 and without any other attendant exertion on the part of the operator.

In instances where gates or the like are adapted to be opened in one direction only, one of the levers 28 is inverted as illustrated in Figure 7 thus permitting the gate to be conveniently pulled open from one side and pushed open from the opposite side.

Without further elaboration the foregoing will

so fully explain the invention that others may, by applying current knowledge, readily adapt the same for use under various conditions of service. Moreover, it is not indispensable that 5 all the features of the invention be used conjointly since they may be employed advantageously in various combinations and sub-combinations.

It is obvious that the invention is not confined to the herein described use therefor as it may be utilized for any purpose to which it is adaptable. It is therefore to be understood that the invention is not limited to the specific construction as illustrated and described as the 15 same is only illustrative of the principles of operation, which are capable of extended application in various forms, and that the invention comprehends all construction within the scope of the appended claim.

20 What I claim is:

In a gate latch, a substantially rectangular shaped casing provided with slots in opposite end walls thereof and having ears struck out from opposite side walls thereof providing openings arranged between the slots and opposite to each other, a latch bar pivoted in said casing and protruding through the slots, said ears being arranged at right angles to the side walls of the casing and extending in opposite directions to each other, and L shaped levers pivoted on the ears with portions thereof extending through the openings and engaging over the bar and the other portions extending upwardly and outwardly from the casing to provide handles 35 for the manual pivoting of said latch bar from either side of the casing.

ROBERT L. SAYLES.
